UNITED STATES PATENT OFFICE

2,283,978

COASTER

Joseph F. Eberle, Westfield, Pa.

Application December 12, 1939, Serial No. 308,869

2 Claims.

(Cl. 16—42)

This invention relates to the art of coasters, and more particularly to those used on the bottom portions of furniture to facilitate easy movement thereof.

Prior coasters, sometimes referred to as tips or shoes, have generally been of metal, or of metal faced with softer materials, such as cotton or felt, but all such prior constructions with which I am familiar have been subject to various disadvantages, such as marring of floors, or damage to rugs, or the accumulation of dirt, or limited life, or complicated construction.

I have discovered that these disadvantages can be overcome and certain additional advantages achieved by providing a coaster having a leather insert therein, as set forth below.

It is therefore an object of my invention to provide a new and improved coaster.

It is another object to provide a coaster having a leather insert.

It is also an object to provide a coaster which is simple in construction, is easily applied, will slide easily, and will not damage floors or rugs.

It is a particular object of my invention to provide a coaster which has a cushioning effect.

It is a further object of my invention to provide a coaster having a cushioned insert that has a convex portion providing a minimum bearing surface on the supporting floor or rug.

It is an additional object to provide a coaster having a leather bearing surface in which the leather is retained in place by its lateral compression.

With the above and other objects in view, which will be apparent as the description proceeds, I have set forth my invention in the following specification, and have illustrated it in the accompanying drawing in which:

Figure 1 is a side elevation of the bottom portion of a piece of furniture provided with my improved coaster, with a portion thereof shown in section on the line 1—1 of Fig. 3;

Fig. 2 is a bottom plan view of my coaster;

Fig. 3 is a top plan view thereof; and

Fig. 4 is a side elevation.

Referring to the accompanying drawing, my improved coaster preferably comprises a metal stamping 10, having a body portion 11 from which prongs 12 are struck out to a position at right angles with said body 11, and a downwardly-extending flange 13.

A leather disc 14 is inserted in the stamping 10 and the flange 13 is then crimped to provide a tight connection between the flange and the leather disc 14. The leather disc 14 is preferably made just slightly smaller in diameter than the original interior dimensions of the stamping, so that a crimping operation will distort the leather disc and give it a concave upper surface 15 and a convex lower surface 16, as best shown in Fig. 1. As also shown therein, the result of the

crimping operation is the provision of a space 17 between the bottom of the stamping 10 and the concave upper surface 15 of the insert. This permits the coaster to have a limited cushioning action when the article 18, to which it is applied, exerts a downward pressure against the leather insert 14.

As will be obvious, the coasters are applied to the legs or other projecting portions of the article 18, which it is desired to equip for a sliding movement, by merely driving the prongs 12 into the said legs.

As will also be obvious from the above, the surface 16, which bears against the floor or rug, is of hard yet compressible sole leather and hence will not scratch or mar the floor or injure a rug, but will enable furniture equipped with these coasters to slide smoothly over any object on which it rests. This sliding is facilitated by the provision of the convex bearing surface 16 and the yielding cushion action discussed above.

In practice, the coaster may be made of any suitable materials, but I prefer to make the metal member by stamping, and to make the insert out of the best grade of sole leather, in view of its long wearing qualities.

In view of their small area, these inserts may be manufactured from waste leather, as for instance, from scraps left in the manufacture of shoe soles.

Although I have herein illustrated the stamping 10 and the leather disc 14 as being of circular construction, it will be understood that these may be made of any other suitable geometrical shape which will accomplish the objects of my invention as set forth above.

As many apparently widely different embodiments of this invention may be made without departing from the spirit thereof, it is to be understood that I do not limit myself to the foregoing embodiments or description except as indicated in the following claims:

I claim:

1. A coaster comprising a stamping, a sole leather bearing insert, and a flange integral with the stamping biting into the side walls of the leather insert to retain the latter in the stamping and give it a concave upper surface spaced from the adjacent surface of the stamping to provide an air space whereby a cushioning effect is obtained.

2. A coaster comprising a metal stamping and an inserted leather bearing surface, the stamping being provided with a circumferential flange which tightly engages the insert and places it under lateral compression to give it a convex bearing surface and a concave upper surface spaced from the adjacent surface of said stamping to provide a cushioning effect.

JOSEPH F. EBERLE.
